HAND BRAKE FOR RAILROAD CARS

Filed Dec. 9, 1931

WITNESS:

BY *Victor J. Evans & Co.*

UNITED STATES PATENT OFFICE

EDGAR B. KEESEY, OF MAMMOTH, WEST VIRGINIA

HAND BRAKE FOR RAILROAD CARS

Application filed December 9, 1931. Serial No. 579,928.

The object of the invention is to provide a manual actuating means for railroad car brakes so designed that the brake setting function may be accomplished always by a downward movement, whereby the brakeman is enabled to exert his strength to the best advantage and runs no risk of being thrown off the car, as is the condition where the brake is set by a lateral pulling movement; to provide a structure of the kind indicated in which the hand actuated element is readily folded down into a position where it is out of the way, irrespective of the elements connected with the brake bar; and to provide a brake actuating means which is of simple form, susceptible of cheap manufacture, and of a character which makes its application possible to conventional car structures without modification thereof.

With this object in view, the invention consists in a construction and combination of parts of which a preferred embodiment is illustrated in the accompanying drawing but to which the invention is not to be restricted. Continued use in practice may suggest certain changes or alterations and the right is claimed to make any which fall within the scope of the appended claim.

In the drawing:

Figure 1 is a front elevational view of the invention, a portion of the car bolster being shown.

Figure 2 is an elevational view looking in a direction at right angles to that in which Figure 1 is viewed, this figure showing the bolster in section.

Figure 3 is a top plan view of the structure of Figure 1.

Figure 4 is a sectional view on the plane indicated by the line 4-4 of Figure 1.

Figure 5 is a perspective view of the rack bar actuating lever.

The frame of the invention comprises the forward and rear standards 10 and 11, each consisting of a bolt 12 and a spacing sleeve 14 to which the bolt 12 extends. The cap member 15 is disposed on top of the spacing sleeves 14 and the bolts pass through this cap member. The bolts of the rear stand-

ards 11, however, after passing through a base plate 16 are seated on top of the bolster 17, also passing through the latter and through a bracket plate 18 disposed against the under face of the bolster. The bolts of the forward standards also pass through the base plate and bracket 16 and 18 but to the front of the bolster and spacing sleeves 19 are disposed between the base plate 16 and bracket plate, so as to lock all these parts together at the forward end.

The cap plate 15 is bent into an inverted U-shaped form at the center, as indicated at 20, the web portion of this U-shaped section being provided with a slot for the passage of a rack 21, terminally provided with a swinging loop 22 which acts as an abutment to limit the forward movement of the rack. The rack is operatively connected by means of the chain 23, with the brake bar to be actuated, this chain being trained over a direction pulley 24 rotatable in the bracket 18. To prevent the chain 23 from dropping off the direction pulley, when the chain is loose, an idler pulley 25 is employed, this being also carried by the bracket 18 and in peripheral engagement with the direction pulley 24. Both the idler pulley 25 and direction pulley 24 are grooved to permit the passage of the chain between them.

The base plate 16, bolster 17 and base portion of the bracket 18 are slotted for the passage of the rack bar 21.

The actuating means for the rack bar consists of a hand lever 26 formed with a circular head portion 27 on a part of whose periphery are formed the teeth 28, the latter meshing with the rack bar in one position of the head 20. The head 27 is formed with the stub journals 29 and these are received in inclined slots 30 formed in the side walls of the U-shaped portion of the cap member 15. When the stub journals are in the bottoms of the slots 30 the teeth 28 are in mesh with the teeth on the rack bar and the lever is extending outwardly in a lateral direction from the rack bar. Therefore, depression of the lever effects elevation of the rack bar and a pull on the chain 23 with resultant movement of the brake beam and setting of the brake.

To take care of the lateral thrust imposed on the brake bar by the actuation of the lever 26, a thrust roller 31 is disposed behind the rack bar in the U-shaped portion of the cap 5 member, and a similar thrust roller 32 disposed behind it just above the plane of the base plate 16, this latter thrust roller being supported on a stud spanning the ears 33 formed on the sleeve 14 of the rear standard 10 11.

A spring actuated dog 34 is pivotally mounted on the base plate 16, the actuating spring 35 being disposed below the foot brake 36 with which the dog is formed. The actuating 15 spring tends to force the nose of the dog towards the teeth of the rack bar, so that the nose is always in position to fall into engagement with a selected tooth. Thus, as the rack bar is elevated by the actuation of the lever 26, the elevated position is preserved by the dog 34, so that the lever, having reached the limit of its possible downward movement, may have its teeth lifted out of engagement with the teeth of the rack bar for sliding the 20 stub journals up the slots 39. Returning the lever to an upwardly inclined position, it may thereafter be moved downwardly to bring the teeth into engagement with the teeth of the rack bar and another movement 25 of the latter effected. This series of operations is continued until the brakes are set with the desired degree of intensity, such set 30 position being maintained by the dog 34.

The brakes may be released by depression 35 on the foot plate of the dog to swing it out of engagement with the rack bar, which will permit the latter to drop and relieve the tension on the chain 23.

When not in use, the lever may be folded 40 down against the rack bar, as shown in full lines in Figure 1, the teeth on its head having been disengaged from the teeth of the rack bar by effecting bodily movement of the lever made possible by the arrangement of the 45 slots 30.

The invention having been described, what is claimed as new and useful is:

A brake actuating device comprising spaced standards having means for anchoring 50 them to the bolster of a car, a cap plate secured to the standards at their upper ends and having a U-shaped web portion, a bar operatively connected with the brake beam and extended through into the U-shaped portion 55 of the cap plate, a roller spanning and carried by said U-shaped portion to constitute a bearing for the upper end of the bar, a similar roller supported between adjacent standards adjacent the bolster, and an actuating lever operatively engaging the bar on the opposite edge from that which engages 60 said roller, said lever having a pivotal mounting in said cap plate.

In testimony whereof I affix my signature.
65 EDGAR B. KEESEY.
